SEWING RACK

Ecce D. Sheline, 2938 Madrona Drive, Longview, Wash.

Filed Sept. 14, 1962, Ser. No. 71,696

Term of patent 14 years

(Cl. D3—19)

FIG. 1

FIG. 2

FIG. 1 is a front perspective view showing my new design for a sewing rack as it appears with one of the drawers in partially opened position.

The back is plain.

The broken line showing of the spools is for illustrative purposes only.

I claim:

The ornamental design for a sewing rack, as shown and described.
